UNITED STATES PATENT OFFICE.

HARRIS S. COY AND JOHN D. GREENLEE, OF ANDERSON, INDIANA.

SPARKING DEVICE.

Application filed October 18, 1920. Serial No. 417,698.

To all whom it may concern:

Be it known that we, HARRIS S. COY and JOHN D. GREENLEE, citizens of the United States, residing at Anderson, in the county 5 of Madison and State of Indiana, have invented new and useful Improvements in Sparking Devices, of which the following is a specification.

The invention relates to improvements in 10 arrangements of electrodes for spark gaps of various forms and types of electrical apparatus, and more particularly to such arrangements thereof involved in spark gaps of spark plugs, or the like, used in ignition 15 systems for internal combustion engines.

The primary object of the invention is to provide for an arrangement of electrodes for spark gaps wherein a greater efficiency, and a more steady and even spark is obtained in 20 ignition systems for internal combustion engines, at both the highest and lowest speeds of the latter, than has heretofore been developed in the use of known devices of like character.

Another object of the invention is to provide for an arrangement of electrodes for spark gaps, and one wherein, in addition to effecting a maximum efficiency to and producing a more steady and even spark in an 25 ignition system, a greater sparking length is produced than has heretofore been the case, and, consequently, better ignition can be obtained for the starting and operation of an engine at extremely low speeds, as well 30 as for the securing of maximum efficiency at the higher or highest speeds.

With the foregoing and other objects in view, the invention resides in the certain novel and useful arrangement and construction of parts as will be hereinafter more 40 fully described, set forth in the appended claims, and illustrated in the accompanying drawing, in which:

Figure 1 is a side elevation of a spark 45 plug embodying the invention,

Figure 2 is a bottom plan view of same,

Figure 3 is a bottom plan view of a slightly modified form thereof, and

Figure 4 is a transverse section taken on 50 the line 4—4 of Figure 3.

Referring to the drawing, in which similar characters of reference designate corresponding parts in the several views thereof, the body of the spark plug may be 55 of any desired or special design and construction, or of conventional form as shown,

and the same consists of a center core 10, of porcelain or other form of insulating material, which is suitably shaped to snugly fit an outer shell 11, the latter having its outer 60 and lower surface screw-threaded for engagement with the plug opening extending through the wall of an engine. The upper inner surface of the metal shell 11 is usually provided with an annular recess 12 65 adapted for the reception of an annular rib 13, formed on the porcelain or insulated core 10, and threaded to receive a bushing or clamping nut 14, which, when threaded into the annular recess 12, clamps the porcelain 70 or insulated core 10 tightly in position within the shell 11. Extending vertically through the porcelain or insulated core 10 is an electrode 15, in the form of a steel or other type of metallic rod, which has its 75 upper end projecting above the end of the core and threaded to receive thereon a knurled nut 16, the latter acting as a binding post for the reception of one of the conductors of the ignition circuit. The lower 80 end of the electrode is generally of reduced diameter, as shown, to provide a sparking point 17. Depending from the lower edge of the shell 11 is a second electrode 18 which is suitably bent or curved so as to bring its 85 free end into proximity to the sparking point 17 to provide a gap of desired sparking length.

In the specific application of the invention to a spark plug as above described, and as particularly shown in Figures 2, 3 and 4, it is contemplated to make use of one or more auxiliary or ionizing electrodes 19 and 20, the electrode 19 being used alone and arranged in desired proximity to the center electrode sparking point 17, as shown in Figures 2 and 3, or in conjunction with the electrode 20, as in Figure 3, in which case, the latter is arranged at one side of the projecting portion of the main electrode 18, both of the electrodes 19 and 20 being insulated from the main electrodes 17 and 18 and from all connection otherwise from the ignition circuit, as by being embedded in or otherwise secured to the porcelain or insulated core 10.

In the operation of the spark plug, or plugs, thus provided, and in the case as in Figure 2, the usual spark gap being indicated at *a*, when potential is impressed at the point 17 of the electrode 15, an "ionizing" 110 spark gap *b* is brought into existence be-

tween the point 17 and the auxiliary or ionizing electrode 19 slightly prior to or almost simultaneously with the establishing of the main spark, and the same effects a more rapid and intensified spark formation than is usual with ordinary types of two point spark gaps. The rapidity and intensity of this spark formation is noticeably increased, when the second auxiliary or ionizing electrode 20 is made use of, as in Figure 3 of the drawing, and in this case a second ionizing spark gap is established between it and the main electrode 18, as at *c*.

In the practical use of the invention, in the use of either or both of the auxiliary or ionizing electrodes 19 and 20, it has been found that the sparking length of the main gap *a* can be increased to a marked degree, with a resultant longer and hotter spark, and that a maximum efficiency of the same is maintained throughout the running of an engine from minimum starting speed to the highest speed of the same. Further, by reason of effecting a more rapid formation of the spark, the minimum rate of turning of the shaft of the engine for starting purposes is less than now found necessary for its accomplishment in the present and known practice. It will be observed that in our device we make use of a central electrode 17 of usual type in connection with a ground electrode 18 also of usual type, and producing the ordinary spark gap *a*, and that in addition we provide, as in Figures 1 and 2, a third insulated electrode 19 arranged at right angles to the electrode 18 and closer to the central electrode 17 to produce another and shorter spark gap *b*, or that, as in Figures 3 and 4, we provide, in addition to the three electrodes named, a fourth insulated electrode 20 arranged at right angles to the electrode 18 to provide a third short spark gap *c* similar to the gap *b*. It will further be observed that the electrodes 18 and 19 are located within the field of electromagnetic force surrounding the electrode 17 and generated in the passage of a current across the gap *a*. This field of force is necessarily largely concentrated in the region of the gap *a*, but exists to an appreciable extent through an arc around the electrode 17 of 90° or more from the gap *a*, in the zone of which the electrode 19 lies, and we have found that in the use of the usual electrodes 17 and 18, with a spark gap *a* of comparatively great length, much of this magnetic force lying outside of the line of gap *a* is dissipated and lost and that there is also considerable loss by grounding through the electrode 18, since all the magnetic force is not consumed in the production of the spark across gap *a*. Our construction makes use of this waste magnetic force directly emitted from electrode 17, beyond the main spark zone *a*, to produce a spark between electrodes

17 and 19 across gap *b*, and of the waste force from electrode 18 to produce a spark between electrodes 18 and 20 across gap *c*. These auxiliary sparks are intensified by induction in the electrodes 19-20 and the resultant ionizing action produced, and we have found that by the arrangement of the auxiliary electrodes 19-20 specified an appreciable ionizing effect is obtained without the necessity of the use of auxiliary electrodes of high capacity. To secure the effect noted, however, it is essential to dispose the electrodes 19-20 with relation to the electrodes 17-18 as described, as otherwise the advantages noted will be lost and no material ionizing and auxiliary sparking actions obtained.

It is further contemplated, in the carrying out of the invention to its fullest extent, and either in lieu of the close association of the "ionizing" spark gaps with the main electrodes of a spark plug, or in conjunction with the same as may be desired, to make use of an ionizing spark gap at any point in the ignition circuit exteriorly of the engine and between the transformer and the spark plug or plugs.

It is also to be noted of the auxiliary or ionizing electrodes 19 and 20, that, in the location of the same as shown, they may be described as being in parallel with respect to the main electrodes 17 and 18 as distinguished from any of such auxiliary electrodes being arranged in series between the main electrodes, although the present electrodes 19 and 20 may be so arranged, if desired.

It is therefore to be well understood that various arrangements, both with regard to number of auxiliary or ionizing electrodes used or their location within the ignition circuit, may be resorted to within the scope of the appended claims for the accomplishment of the desired objects and results and without departing from the spirit and scope of the same.

Having thus fully described the invention, what is claimed, is:—

1. A spark plug having a central electrode, a main ground electrode having a point arranged radially to the central electrode and disposed to form a main spark gap therebetween, an insulated electrode having a spark point arranged radially to the central electrode to form a spark gap therebetween of less length than and arranged at right angles to the first-named spark gap, and a second insulated electrode having a spark point disposed at right angles to the spark point of the ground electrode and also forming therebetween a spark gap of less length than the main spark gap.

2. In an electrical sparking device, a pair of spaced electrodes forming a main spark gap therebetween and constituting the oppo-

site terminals of an ignition circuit, and a pair of auxiliary electrodes, one arranged at one side of and in proximity to one of the main electrodes and forming an ionizing 5 spark gap therebetween, and the other arranged at one side of and in proximity to the other main electrode and forming an ionizing spark gap therebetween, said auxiliary electrodes being insulated from said 10 main electrodes and from said ignition circuit.

3. In an electrical sparking device, a pair of spaced electrodes forming a main spark gap therebetween and constituting the opposite 15 terminals of an ignition circuit, and auxiliary electrodes spaced at one side of each of said main electrodes and forming ionizing spark gaps therebetween, one of said auxiliary electrodes being disposed with respect to its complemental main electrode at the side thereof opposite to that of the other of said auxiliary electrodes with respect to its complemental main electrode, said auxiliary 20 electrodes being insulated from said main electrodes and from said ignition circuit.

25 4. In a spark plug, the combination with the shell and insulated core thereof, of spaced electrodes forming a main spark gap 30 therebetween and constituting the terminals of an ignition circuit, and auxiliary elec-

trodes spaced at one side of each of said main electrodes and forming therebetween ionizing spark gaps at right angles to the path of said main spark gap, one of said auxiliary electrodes being disposed with respect to its complemental main electrode at the side thereof opposite to that of the other of said auxiliary electrodes with respect to its complemental main electrode, said auxiliary 35 40 electrodes being insulated from said main electrodes and from said ignition circuit.

5. In an electrical sparking device, a pair of spaced main electrodes, to wit, a central electrode and a ground electrode arranged 45 at one side of said central electrode, forming a main spark gap therebetween and constituting the opposite terminals of a supply circuit, an auxiliary electrode arranged at one side of the central electrode at an angle 50 to the ground electrode and forming with said central electrode an ionizing spark gap, and a second auxiliary electrode arranged at an angle to the ground electrode and forming therewith a second ionizing spark gap, said 55 auxiliary electrodes being insulated from said main electrodes and from said supply circuit.

In testimony whereof we affix our signatures.

HARRIS S. COY.
JOHN D. GREENLEE.
